DES. 1941

Elmer F. Key of Lowell, Mass.
Assignor to

The Lowell Manufacturing Company, of the same place.

Letters Patent No. 121944 Dated May 10, 1864.

Design for a Carpet Pattern.

The schedule referred to in these Letters Patent and making part of the same.

To all whom it may concern:

Be it known that I, Elmer F. Key, of Lowell, in the County of Middlesex, and State of Massachusetts, have originated and designed a new pattern for carpets or other fabrics, of which the following is a full, clear and exact description, reference being had to the accompanying drawings, making part of this specification.

A is an oblong Persian set figure resting on the ground 1, which also supports small scrolls and has a scalloped border.

In the centre of figure A, is a small plain rosette 2. Surrounding the ground 1, is the figured frame 3, to the inner edge of the upper and lower parts of which are attached the groups of sprigs 4, 5.

Lying between the sides of frame 3 and the ground 1, are the groups of flowers and leaves 5, 5.

6. is an eight pointed set figure, bordered with small irregular figures and surrounded by the frame 7, which rests

2 on a ground composed of alternate rows of small balls and waving ferns.

DES. 1941

The plain frame 8 encloses the ground of balls and ferns.

B and C at the sides are halves of figures similar to A.

D and E are halves of figures similar to figure 6, and have similar surroundings.

G and H are halves of frames similar to frame 8.

II, II, II, II, are leaves which rest on coral work occupying the remaining portions of the design.

The colors employed for the different portions of the design, may be varied to suit the taste and wish of the manufacturer.

Claim.

What I claim as my invention and desire to secure by Letters Patent, is The design or pattern for carpets or other fabrics, herein set forth.
